US00D809149S

(12) **United States Design Patent** (10) Patent No.: **US D809,149 S**
(45) Date of Patent: ** Jan. 30, 2018

(54) **KNEE JOINT SUPPORTER**

(71) Applicants: **KOWA COMPANY, LTD.**, Aichi (JP);
ADVANCING INC., Osaka (JP);
DMCHAIN COOPERATIVE,
Ishikawa (JP)

(72) Inventors: **Kenta Tsuzuranuki**, Tokyo (JP);
Hitoshi Ojima, Osaka (JP); **Hidegori Kaseno**, Kahoku (JP)

(73) Assignees: **KOWA COMPANY, LTD.**, Nagoya-shi (JP); **ADVANCING INC.**, Osaka (JP);
DMCHAIN COOPERATIVE, Kahoku-shi (JP)

(**) Term: **15 Years**

(21) Appl. No.: **35/501,089**

(22) Filed: **Dec. 16, 2015**

(80) **Hague Agreement Data**

Int. Filing Date: **Dec. 16, 2015**

Int. Reg. No.: **DM/090016**

Int. Reg. Date: **Dec. 16, 2015**

Int. Reg. Pub. Date: **Jun. 17, 2016**

(30) **Foreign Application Priority Data**

Jun. 26, 2015 (JP) 2015-014230

(51) **LOC (11) Cl.** **24-00**

(52) **U.S. Cl.**

USPC **D24/190**

(58) **Field of Classification Search**

USPC D24/190, 231, 189; D14/411; 602/19,
602/14

See application file for complete search history.

(57) **CLAIM**

The ornamental design for a knee joint supporter, as shown and described.

DESCRIPTION

1. Knee joint supporter
1.1 is a front view;
1.2 is a back view;
1.3 is a left view;
1.4 is a right view;
1.5 is a top view;
1.6 is a bottom view;
1.7 is a perspective view;
1.8 is a front view shown in an environment; and
1.9 is another front view shown in an environment.
In the reproductions, the stippling feature indicates a contrast in appearance. In 1.1 through 1.7 the broken lines are for the purpose of illustrating a stitching feature and form a part of the claimed design. In 1.8 through 1.9 the broken lines are for the purpose of illustrating environment only and form no part of the claimed design.

1 Claim, 9 Drawing Sheets
